UNITED STATES PATENT OFFICE.

LOUIS JOSEPH EMMANUEL COLARDEAU AND JULES RICHARD, OF PARIS, FRANCE.

DISPLAY DEVICE.

1,073,331.

Specification of Letters Patent. Patented Sept. 16, 1913.

Application filed July 27, 1911. Serial No. 640,911.

To all whom it may concern:

Be it known that we, LOUIS JOSEPH EMMANUEL COLARDEAU, of 13 Rue de Navarin, professor at the College Rollin, and JULES RICHARD, of 25 Rue Mélingue, instrument maker, both in the city of Paris, Republic of France, have invented an Improved Display Device, of which the following is a full, clear, and exact description.

- 10 This invention relates to an operating device applicable to apparatus for classifying and distributing intended for the examination of photographic views particularly stereoscopic views, in which the views to be examined are withdrawn one by one from a box in which they are arranged, lifted to a level with the eye pieces and brought toward them which permits of employing short focus eye pieces.
- 15 20 This apparatus comprises a carriage with horizontal movement supporting the box in which the views are arranged and capable of advancing uniformly by the distance which separates two consecutive views each time the operating mechanism is acted upon in such a manner that each view is brought in succession into the plane of a frame with vertical movement; this frame is intended to lift the view and engage it in a second frame with horizontal movement which causes it to approach the lenses of the stereoscopic system.
- 25 30 35 40 45 50 The operating device which actuates the parts of an apparatus such as described above is characterized broadly by the fact that the frame with vertical and the frame with horizontal movement are each actuated by a connecting rod and a crank plate which are given their movement alternately from a single operating crank. By means of an appropriate device the two crank plates can be driven in succession by the driving crank. In the preferred embodiment of the invention the driving crank drives two rings rotating together and carrying on half their periphery only sets of teeth arranged at an angle of 180° to each other and able to engage with two separate pinions respectively integral with the two crank plates.

55 The invention is illustrated but by way of example only in the accompanying drawing in which:

Figure 1 is a front elevation of the apparatus with the box containing it and the stereoscopic system removed. Fig. 2 is a corresponding side elevation. Fig. 3 is a

side elevation on the opposite side to the foregoing. Fig. 4 is a longitudinal section. Fig. 5 is a detail rear elevation of the frame with vertical movement. Fig. 6 is a similar view to Fig. 4 showing the operation. Fig. 7 is a side elevation of the operating mechanism. Fig. 8 is a section on the line A A in Fig. 7. Figs. 9 to 13 are detail views showing the arrangement of the toothed wheels and pinions of the mechanism. Figs. 14 to 17 are detail views showing the means for retaining the views in the frame with horizontal movement.

As shown in the drawing the views *a* to be examined are contained in a box *b* mounted on a carriage *c* adapted for horizontal displacement on fixed slideways *c*¹. A rack *c*² is fixed to this carriage and meshes with a pinion *d* (Fig. 4); this pinion is keyed to a shaft *d*¹ which also carries a star or Maltese cross wheel *e*. This wheel can be actuated by means of a pin *f* (Fig. 3) intended to engage in the notches in the wheel; this pin is carried by a spring *f*¹ mounted on a crank plate *g*; it passes through a recess in the plate *g*, and projects toward the interior.

The bottom of the box *b* is recessed in such a manner as to permit of the passage of the branches *h* (Figs. 1 and 4) constituting an extractor and forming part of the frame *i* with vertical movement; the latter is movable in slideways *i*¹ (Fig. 4); it is operated by a lever *i*² (Figs. 1 and 5) rotating upon a fixed shaft *i*³ and a rod *i*⁴ pivoted to the crank plate *g*.

A spring *i*⁵ acting upon the lever *i*² balances the weight of the frame *i*.

The frame *j* with horizontal movement is guided by rods *j*¹ sliding in fixed supports *j*² (Fig. 2); it is controlled by arms *j*³ keyed to a rotary shaft *j*⁴. A connecting rod *k* is pivoted to one of these arms and also to a crank plate *l*. In each side this frame *j* carries a rocking flange *m* (Figs. 14 to 17) normally maintained horizontal by a spring *m*¹; these flanges move aside when inclined *m*² (Fig. 6) carried by the vertical frame *i* come into contact with them.

The crank plate *g* is keyed on a shaft *n* at the end of which is keyed a pinion *o* (Fig. 7). The crank plate *l* is rigidly connected with a pinion *o*¹ arranged beside the foregoing. These two pinions which are independent of each other mesh respectively with two toothed wheels *p* *p*¹ integral one with the other and provided with sets of

teeth q q^1 upon half their periphery only as shown in Figs. 7 and 8.

The two toothed wheels p p^1 are driven by a double pinion r controlled by a handle s . The numbers of teeth in the gears q q^1 , o o^1 r are such that two revolutions of the pinions o o^1 r correspond to one revolution of the wheels p p^1 . It follows from this arrangement that on giving two turns to the handle s and consequently to the pinion r in either direction (1) the two wheels p p^1 make one revolution the pinion r meshing in succession with the teeth q and the teeth q^1 ; (2) during half a revolution made by the wheels p p^1 one of the sets of teeth q or q^1 meshes with one of the pinions o o^1 and causes it to make a revolution and during the other half the other set of teeth q or q^1 meshes with the second of the pinions o o^1 . Consequently by rotating the crank s continuously the pinions o o^1 make a revolution alternately. The pinion which does not rotate is held absolutely motionless owing to the circular slots t^1 presented by cheeks t (Figs. 12 and 13) integral with the pinions; the circular edges of cheeks u carried by the wheels p p^1 engage in these slots.

The operation of the apparatus is as follows: Assuming that the last plate examined has just been replaced in the box b and that the carriage c has advanced by the interval separating two views the parts of the apparatus will occupy the position represented in Figs. 1, 2, 3, 4 and 5; the frame i for vertical movement is depressed; the frame j for horizontal movement is brought against it; the rocking flanges m strike against the inclines m^2 and are pressed aside as shown in Figs. 14 and 15. If the crank s be then rotated in the direction indicated by the arrow 1 (Fig. 2) in the first place the vertical frame i is lifted. At this moment the teeth q are in mesh with the pinion o ; the wheel p leaving the position represented in Figs. 7 and 10, half the set of teeth q come into mesh with the teeth of the pinion o causing the latter to effect a half revolution and during this time the pinion o^1 remains motionless. The pinion o making a half revolution the shaft n and the plate g keyed upon this shaft also rotate through a half revolution. This movement of the plate g causes the descent of the rod i^4 (Fig. 3, arrow 4) the rocking of the lever i^2 (Fig. 5) and the ascent of the frame i . In this upward movement the branches of the extractor h lift a plate and cause it to participate in the movement of ascent. This plate engages in slideways v (Figs. 4 and 15) in the frame j ; the flanges m being pressed aside allow the plate to engage in the plate j . At the end of the upward movement the extremities of the inclines m^2 come opposite the flanges m ; the latter spring back and assuming the position shown in Fig. 17 support

the plate below. In continuing to rotate the handle s in the same direction the frame j is displaced horizontally. This result is obtained by the meshing of the gear p^1 with the pinion o^1 which causes the plate l to rotate in the direction indicated by the arrow 5 in Fig. 2; the rod k presses the arm j^3 in the direction indicated by the arrow 6 which displaces the frame j toward the left (Fig. 2) and brings it into the position represented in Fig. 6. In this position the view is brought closer to the eye pieces; by leaving the handle s at rest the view contained in the frame j can be examined for any desired length of time. The horizontal displacement of the frame j is produced by a half turn of the plate l ; by completing the rotation of the plate the rod k displaces the frame j in the direction 7 (Fig. 6) and applies it against the frame i . The pivot k^1 of the rod k presents a certain amount of play in such a manner that in the rotation of the crank s when the pivot k^1 occupies its two extreme positions it is situated in a certain dead angle; the crank can then be rotated through this angle without displacing the frame j . When the frame j again comes against the frame i as stated above the flanges m bear against the extremities m^2 of the inclines of the frame i . By rotating the handle s still in the same direction the teeth q again act upon the pinion o , the plate g effects a half revolution and the rod i^4 depresses the frame i ; from the commencement of the movement the inclines m^2 depress the flanges m in such a manner that the plate is no longer retained in the frame j and rests upon the branches h ; the plate descends with the frame i and resumes its place in the box b . At the end of this movement the pin f engages in a notch in the wheel e and causes it to rotate to the extent of one division. The pinion d then causes the rack c^2 and the carriage c to advance by the amount of the interval comprised between two successive views, in such a manner that by repeating the operations that have just been described the following plate is brought in front of the eye pieces and so on in succession.

The novel device is very simple and strong. It presents the advantage of operating silently in both directions on rotating the handle s in one direction or the other. It is possible to commence a movement, to interrupt it, to go back and so forth without any difficulty.

When all the views have been examined the carriage c has reached the end of its movement. The views can then be examined in reversing the direction or the carriage can be brought into its initial position by disengaging it from the driving mechanism in any convenient manner.

The arrangements described are not only

applicable to apparatus for examining views but also to similar devices intended for projecting them.

The arrangements indicated above are given by way of example only and the forms, dimensions and detail arrangements can vary in every case without affecting the principle of the invention.

We claim:

- 10 In a classifying and distributing apparatus for photographic views, a box in which the views are arranged, a horizontally movable carriage carrying said box, a vertically movable frame for lifting successively each view, eye pieces, a horizontally movable frame for bringing said view near the eye-pieces, a connecting rod and crank plate device for each frame, pinions respectively
- 15

connected with the crank plates, a system of two toothed wheels connected together and provided with teeth on one half of their periphery said pinions engaging with said first mentioned pinions, an operating crank and a pinion for simultaneously actuating the two toothed wheels.

20
25 The foregoing specification of our improved operating device for use in connection with apparatus for classifying and distributing photographic views or the like, signed by us this eighth day of July 1911.
